OPEN-HEARTH FURNACES AND CHARGING MEANS

Frederick A. Daggett, Jr., and Jack R. Lythgoe, Johnstown, and Martin E. Kiehl, Friedens, Pa., assignors, by mesne assignments, to Bethlehem Steel Corporation, a corporation of Delaware

Filed Mar. 6, 1964, Ser. No. 349,908
2 Claims. (Cl. 263—40)

This invention relates in general to metallurgical furnaces and in particular to improvements in the construction of open-hearth furnaces.

Broadly, our invention comprises providing, integral with the charging wall of a furnace, a hot metal chute which extends from the front of the charging wall, through the charging wall, downwardly into the hearth of the furnace. By this means molten pig iron can be charged directly into the molten metal bath in the furnace without moving any of the vertically slideable doors from in front of the charging openings and without the hot metal coming into contact with the banks of the furnace. Furthermore the charging of hot metal into the furnace by this means will not require the use of the charging machine, conventional charging bowl and conventional charging trough.

It is therefore the primary object of this invention to provide a novel and improved furnace charging wall construction which will permit efficient charging of hot molten metal into the molten metal bath in the hearth of the furnace.

It is another object of this invention to provide a novel and improved furnace charging wall construction which will permit the charging of hot metal directly into the molten metal bath in the furnace to be accomplished in a minimum amount of time in a safe and efficient manner without contacting the bank of the furnace.

FIGURE 1 shows a partial front elevation of the charging wall of an open-hearth furnace.

FIG. 2 is a sectional view taken along line 2—2 of FIG. 3 in the direction of the arrows.

FIG. 3 is a sectional view of a portion of the interior of the charging wall embodying the invention.

FIG. 4 is a sectional view taken along line 4—4 of FIG. 1 in the direction of the arrows.

Referring now to FIG. 1, the charging wall of an open-hearth furnace is designated by the numeral 10. The hot metal chutes are shown generally at 11 integral with the charging wall 10 of the furnace at each end thereof and beyond the water-cooled vertically slideable doors 13 which cover the standard charging openings of the furnace.

A partial top sectional view of the open-hearth furnace, FIG. 2, shows one of the integral hot metal chutes. The hot metal chute consists of a refractory-lined steel lip 14 and a refractory-lined trough 15 extending through the charging wall 10 of the furnace. The refractory-lined trough 15 communicates with a refractory-lined trough 18 formed in the built-up bank 16 of the furnace through a hole in the charging wall 10. It is essential to build the refractory-lined trough 18 in the bank 16 of the furnace so that the molten pig iron will be charged directly into the molten metal bath in the furnace, thus avoiding contact with the bank of the furnace which would cause early erosion of the bank. The refractory-lined steel lip 14 of the hot metal chute extends a short distance in front of the charging wall 10 of the furnace to provide easy pouring of the molten metal from the ladle. However, the lip does not extend out from the furnace wall so far as to impede the movement of the charging buggies and the charging boxes thereon in front of the furnace.

FIG. 3 is another view of the integral hot metal chute from inside the furnace showing more clearly the built-up bank and the position of the refractory-lined trough 18 in the bank 16 of the furnace. The refractory-lined trough 18 extends a short distance below the level of the hot metal bath shown generally at 24. This construction assures the introduction of the molten pig iron into the hot metal bath 24 without coming into contact with the bank of the furnace.

Referring to FIG. 4, the curved and warped steel plate 19 supports the refractory lining 20 of the lip 14. The refractory lining 20 is continued in the trough 15 and is supported by the charging wall 10 of the furnace. The composite steel plate assembly shown generally at 21 supports the refractory-lined charging wall 10 of the furnace at the opening 22 in the charging wall 10 of the furnace through which the refractory-lined trough 15 extends into the furnace. The vertical buckstays 23 on each side of the chute support the charging wall 10 of the furnace and the hot metal chute 11.

When it is desired to charge molten metal into the furnace, a transfer ladle is filled with hot metal from the hot metal mixer located at one end of the shop. The overhead floor crane in the shop transports the ladle filled with molten metal to the furnace requiring the hot metal addition. The ladle is positioned in front of the hot metal chute so that when it is rotated about its trunnions, acting as pivot points, the hot metal will be poured into the lip 14 of the integral hot metal chute 11 down the trough 15 communicating with the curved refractory-lined trough 18 and into the molten metal bath 24 in the furnace hearth 17 through the opening 22 in the charging wall of the furnace.

Although we have referred in general to a refractory-lined integral hot metal chute, we prefer to use a magnesite brick lining, but it will be understood that other linings such as chrome and the like brick or rammed mixes may be used with equally good results.

Incorporating two hot metal chutes, as shown herein, makes it possible to charge hot metal into the molten metal bath in the furnace from both ends of the charging wall of the furnace at the same time, decreasing the time required for making the addition. Although we have shown an open-hearth furnace with two integral hot metal chutes, it is within the scope of this invention to incorporate only one integral hot metal chute at either end of the charging wall of the furnace.

We claim:

1. An open-hearth furnace having a charging wall and charging openings in said charging wall through which solid raw materials are charged into the hearth of the furnace, a built-up bank on the end of said charging wall in said furnace and a chute for charging hot metal into the furnace, said chute comprising a refractory-lined steel lip and a refractory-lined trough a first portion of which extends from said lip through the charging wall of the furnace communicating and integral with a second portion in the bank of the furnace, said hot metal chute being integral with the charging wall of the furnace.
2. An open-hearth furnace having a charging wall and charging openings in said charging wall through which solid raw materials are charged into the hearth of the furnace, a built-up bank on the end of said charging wall and means for charging hot molten metal into the molten metal bath in the furnace, said means comprising a hot metal chute integral with the charging wall of the furnace, said hot metal chute comprising a refractory-lined warped and curved steel plate forming the lip of the chute, said lip extending out from in front of the charging wall of the furnace, a refractory-lined trough having a first portion extending from the said lip through the charging wall of the

furnace and communicating with a second portion of refractory-lined trough in the bank of the furnace.
